E. HARTMETZ

BLOWER

Filed May 12, 1927

Inventor:

Ernst Hartmetz

by Heinrichs

Atty.

UNITED STATES PATENT OFFICE.

ERNST HARTMETZ, OF OBERESSLINGEN-ON-THE-NECKAR, GERMANY.

BLOWER.

Application filed May 12, 1927, Serial No. 190,856, and in Germany May 17, 1926.

My invention relates to blowers, and more particularly to appliances by which a fluid under pressure is projected onto a surface. It is an object of my invention to provide 5 an appliance of the kind described which requires only little power for its operation and prevents fatigue to the operator, and in which the life of the control valve is much increased.

10 To this end, instead of the usual arrangement with the axis of the control valve transversely to the axis of the appliance, I provide a valve which is arranged longitudinally or coaxially with respect to the 15 appliance. With this arrangement of the valve, I not only provide a convenient arrangement of its operating lever in a slot of the appliance, but I also prevent obnoxious action of the fluid under pressure on the 20 valve and its seat.

Preferably the arrangement of the valve is such that the fluid under pressure tends to hold the valve on its seat, and, if desired, a spring may be provided for assisting this 25 action.

By way of example I shall now describe a pneumatic appliance such as is used in workshops, foundries and the like, for instance, for blowing chips or other foreign 30 matter out of drilled or bored holes, or away from surfaces, for cleaning pattern plates, etc., but I am not limited to any particular application of my appliance nor to the use of any particular fluid under pressure.

35 In the drawings affixed to this specification and forming part thereof an appliance embodying my invention is illustrated diagrammatically by way of example.

In the drawings 40 Fig. 1 is an axial section of the appliance, Fig. 2 is a partial section on the line II-II in Fig. 1,

Fig. 3 is an elevation, partly in section, 45 of the control valve, on a larger scale, and

Fig. 4 is a section on the line IV-IV in Fig. 1, with the operating lever removed.

Referring now to the drawings, *a* is a 50 tubular teat to which air under pressure is supplied by a flexible tube (not shown), *b* is the valve casing which is screwed on the front end of the teat *a*, *c* is a nozzle support which in turn is screwed on the front end

of the valve casing, and *p* is a nozzle secured in the front end of the support.

The control valve *e* is equipped with a 55 valve spindle *d* secured in the valve body by means of its threaded end, and a washer *f* which is held between a flange *g* of the valve spindle *d* and is secured in the valve by a peripheral shoulder *h*. As will appear 60 from Fig. 1, the valve and its spindle are arranged coaxially with the casing of the appliance so that erosion of the valve face by the fluid under pressure, as with the usual transverse arrangement of the valve, 65 is eliminated. It is not necessary though generally preferable that the valve be arranged coaxially, but it is important that it should be arranged longitudinally with respect to the casing of the appliance. The 70 fluid in rushing past the valve tends to pull the washer *f* out of the valve body but this tendency is overcome by the flange *g* and the shoulder *h*.

The control valve cooperates with an annular seat *k* in the valve casing *b* and is held on its seat by the joint action of a spring *i* and the fluid pressure from the teat *a*. The valve spindle *d* is free to slide in a bushing *l* which projects from the rear 80 end of the nozzle support *c*. *m* is a parallel slot formed intermediate two partitions in the nozzle support *c* as will appear from Fig. 4. A chamber *s* is formed intermediate the valve casing *b* and the nozzle support *c*, 85 and connected with the valve seat *k* by a passage *t* surrounding the bushing *l*, and with the cavity *u* of the nozzle support *c* by two passages *v*, *v* which extend along the walls of the slot *m* on either side of the slot 90 *m*, as shown in Fig. 4. *o* is a pin extending through the slot *m* on which the valve-operating lever *n* is free to rock.

As will appear from Fig. 1, the lever is 95 L-shaped and, with its rear face, engages the end of the valve spindle *d* so that when the end of the lever is depressed, the valve *e* will be lifted from its seat *k* and allow compressed air from the teat *a* to flow through the several passages as described and to be finely discharged from a nozzle *p* at the front end of the support *c*. On account of the considerable leverage of the lever *n*, a 100 slight pressure on the lever will open the

valve so that the operation of the appliance is not fatiguing. The head of a screw *r* forms a check for the downward motion of the lever *n* so that the maximum delivery 5 of the valve is limited.

The nozzle *p* is screwed into the front end of the nozzle support *c* and a suspending hook *q* may be inserted between the nozzle and the nozzle support, and clamped in any 10 desired position.

I wish it to be understood that I do not desire to be limited to the exact details of construction shown and described for obvious modifications will occur to a person 15 skilled in the art.

I claim:—

1. A blower comprising a valve casing, means for supplying fluid under pressure to said casing, a nozzle support on said 20 valve casing having a fluid passage way, a bushing projecting from the rear end of said support, a control valve in said valve casing, a spindle secured to said valve and carried in said bushing, said control valve being arranged longitudinally with respect 25 to said blower and so as to be held on its

seat by the pressure of the fluid, the body of said blower containing a slot, and an operating lever in contact with said spindle and arranged pivotally within said slot. 30

2. A blower comprising a valve casing having a fluid passage way, means for supplying to said casing fluid under pressure, a nozzle support on said valve casing, a bushing projecting from the rear end of 35 said support, a control valve in said valve casing, a spindle secured to said valve and guided in said bushing, said control valve being arranged longitudinally with respect to the blower and so as to be held on its 40 seat by the pressure of the fluid, the body of said blower containing a slot, a pin at one end of said slot, and an angular operating lever partly arranged within said slot in contact with said spindle and fulcrumed 45 on said pin, the end of the lever which projects from said slot being directed oppositely to the direction of flow of fluid in said blower.

In testimony whereof I affix my signature.

ERNST HARTMETZ.
